(57) **CLAIM**

The ornamental design for a cell phone protector case with three dimensional spider-bite, as shown and described.

DESCRIPTION

FIG. 1 is a rear perspective view of a cell phone protector case with three dimensional spider-bite showing my new design; FIG. 2 is a front perspective view thereof;

FIG. 3 is rear elevational view thereof;

FIG. 4 is a front elevational view thereof;

FIG. 5 is an elevational view of a left side thereof;

FIG. 6 is an elevational view of the right side thereof;

FIG. 7 is a top plan view thereof;

FIG. 8 is a bottom plan view thereof;

FIG. 9 is a rear exploded view thereof, the three-dimensional spider-bite being removed from the cell phone protector case; and,

FIG. 10 is a front exploded view thereof, the three-dimensional spider-bite being removed from the cell phone protector case.

The broken lines throughout the figures are shown to illustrate portions of the cell phone protector case and form no part of the claimed design.

1 Claim, 8 Drawing Sheets
